UNITED STATES PATENT OFFICE.

RANDOLPH CROMPTON, OF WORCESTER, MASSACHUSETTS.

HARNESS MECHANISM FOR LOOMS.

No. 809,933.

Specification of Letters Patent.

Patented Jan. 16, 1906.

Application filed June 15, 1904. Serial No. 212,692.

To all whom it may concern:

Be it known that I, RANDOLPH CROMPTON, a citizen of the United States, residing at Worcester, county of Worcester, and State 5 of Massachusetts, have invented an Improvement in Harness Mechanism for Looms, of which the following description, in connection with the accompanying drawings, is a specification, like letters on the drawings representing like parts.

This invention relating to harness mechanism for looms has for its object to improve and simplify the construction of the connections intermediate the harness levers or jacks 15 and the upper sides of the harness-frames, said connections, as shown, comprising a sector having a notched extension and a sheave.

The sector is so shaped as to have connected with it the strapping leading to opposite 20 ends of the harness or heddle frames, one of the straps—the longer one—being connected with one part of said sector-lever and being extended from and sustained by a sheave. By notching the extension of each sector, as 25 shown, the usual cording having loops at its end may be readily moved to engage any notch of the extension of the sector, thus providing for opening the shed more or less wide and providing for lifting any harness-frame 30 to any extent without relation to the other adjoining harness-frame, if such should be necessary.

Figure 1, in side elevation, represents a loom embodying my invention; and Fig. 2 a detail 35 of the sector detached.

The notched harness levers or jacks B, sustained on a rod B', may be moved in any manner, the means herein outlined being common to woolen looms where revolving 40 cylinder-gears actuate vibrator-gears joined by connectors to said levers.

The arch A² of the loom-frame has a stand d, that sustains a rod d', on which is mounted a series of sectors, each comprising two arc-shaped portions d³ d⁴ and a notched extension 45 d². The strap e, connected with the right-hand end of the harness-frame C, is secured to the portion d³, and the strap e', connected with the opposite end of said harness-frame, 50 is attached to the portion d⁴. The strap e' is sustained between the harness-frame and the sector on a sheave f, free to rotate about a stud f'. The extension or arm of each sector is notched, so that the links h at one end of 55 the cords or straps h', attached at its opposite end by link h² to a harness-jack, may be

moved over said extension d² to engage any one of the notches therein to provide for lifting the harness-frame for any desired distance. For instance, by placing the link h² 60 of the connector in the highest notch of the harness-jack and the link h in the lowest notch of the extension d² of the sector I can raise the harness-frame into its highest position possible, a position much higher than 65 though the link h² were simply placed in the highest notch of the harness-jack and then led in usual manner to the harness-frame. So, also, it will be understood that by placing the link h² in the lower notch of the harness-jack and in the highest notch of the extension d² I secure the smallest possible 70 opening of the shed. Providing the extension with notches enables the manipulation of each harness-frame that it may be raised 75 to exactly the desired point.

There is a lever and sheave for each harness-frame, and the straps are connected with sectors, so that both straps are wound on the sectors when the lever is turned in one 80 direction through a moving harness lever or jack, said straps being unwound from said sectors when said levers are moved in the opposite direction to effect the descent of a harness-frame. The jacks B at their lower ends 85 are connected with extensions t of sectors t', turning about a fulcrum t². The extensions are notched, as described, with relation to the sectors having the portions d³ d⁴, and it will be understood that the loops a³, attached 90 to the hooks or wires a², must be adjusted in the notches of the extension to correspond with the positions of the loops h of the straps h' in connection with the extensions d². The levers B have attached wires a, that engage 95 straps a', extended over pulleys a^x, the strap a' being connected with the wires a², referred to.

Having fully described my invention, what I claim as new, and desire to secure by Letters Patent, is—

1. In a loom, a set of sheaves, and a set of sectors mounted above the harness-frames, straps directly connecting the sectors to one end of the harness-frames, and other straps 105 passing over said sheaves and connecting the sectors to the opposite end of the harness-frames, said sectors having notched extensions with either notch of which may be engaged a part of the harness-connecting cords 110 to thereby vary the extent to which any harness-frame may be raised.

2. In a loom, a set of notched harness-levers, a set of harness-frames, a series of sheaves, a series of sectors having notched extensions and disposed between said jacks and harness-frames, connections between said notched jacks and said notched sectors and adjustable in the notches of said jacks or sectors for the purposes set forth, and straps directly uniting the sectors to the harness-frames at one end, and other straps united with said sectors passed thence over said sheaves and joined to the harness-frames at their other end.
3. In a loom, a set of harness-jacks, a set of harness-frames, a series of sheaves and a series of sectors having notched extensions and disposed between the jacks and harness-frames, connections between the said extensions and jacks, and straps directly connecting the sectors to one side of the harness-frame and other straps passing over said sheaves and connected to the other side of said frame and the sectors.
4. In harness mechanism for looms, a harness-frame, a harness-lever, another lever, a strap attached to one end of said frame and led directly to and connected with said other lever, a sheave, and a second strap attached to the opposite end of said harness-frame and led over said sheave and connected with said other lever.
5. In harness mechanism for looms, a harness-frame, a sector-lever mounted on the loom-frame over said harness-frame, a sheave sustained at the top of the loom-frame, two

straps connected with such harness-frames near its opposite ends, each of said straps being united to said sector-lever, one of said straps being passed over said sheave whereby when said lever is moved in one direction, both said straps will be wound thereon and raise the connected harness-frame.

6. In harness mechanism for looms, a harness-frame, a sector-lever mounted on the loom-frame above said harness-frame, a harness-lever, means to connect said harness-lever with said sector-lever, a sheave, and straps connected with said harness-frame and with said sector-lever, one of said straps passing over said sheave, the ends of both said straps being wound on the lower sector-shaped end or part of said lever.

7. In a loom, a set of harness-frames, a set of sheaves, and a set of sectors mounted above the harness-frames, said sectors having notched extensions with either notch of which may be engaged a part of the harness-connecting cords to thereby vary the extent to which any harness-frame may be raised, a sector-lever located below the harness-frame and having notched extensions, and means connecting said extensions and harness-levers.

In testimony whereof I have signed my name to this specification in the presence of two subscribing witnesses.

RANDOLPH CROMPTON.
